INVENTOR:

OSCAR E. FORREST,

BY *Alfred S. Davis*
HIS ATTORNEY.

UNITED STATES PATENT OFFICE.

OSCAR E. FORREST, OF SCHENECTADY, NEW YORK, ASSIGNOR TO GENERAL ELECTRIC COMPANY, A CORPORATION OF NEW YORK.

FUSE-HOLDER.

1,217,741.

Specification of Letters Patent. Patented Feb. 27, 1917.

Application filed December 26, 1912. Serial No. 738,515.

To all whom it may concern:

Be it known that I, OSCAR E. FORREST, a citizen of the United States, residing at Schenectady, county of Schenectady, State of New York, have invented certain new and useful Improvements in Fuse-Holders, of which the following is a specification.

My invention has reference to inclosed fuses for high potential circuits and more especially to means for removing the fuse which is readily attached to and detached from the same. With fuses, such as are commonly used in station wiring, pole work and in subway work, it is frequently desirable to remove the fuse without switching off the current, and, when the same is used on high tension circuits, direct contact with the shell of the fuse is liable to result in a shock to the operator. My invention provides a cheap and effective insulated hand-grip, which is readily secured to the fuse and is easily detached therefrom, whereby the fuse may be removed from the base without danger to the operator.

My invention is illustrated in the accompanying drawings, in which Figure 1 is a vertical sectional view of the fuse box, with the fuse and the attached handle in elevation, and Fig. 2 is an end elevation of the inclosed fuse and the handle therefor.

Referring to the drawings, 1 represents the box within which the fuse is mounted, provided with a cover 2 and with suitable openings 3 for the cables. A base 4 of suitable insulating material, such as wood, is secured to the bottom of the box 1, and contact terminals 5 are mounted on either end of the base. The wood is preferably treated as with paraffin to improve its insulating value. An inclosed fuse comprising an elongated shell 6, the ends of which are closed by caps 7, is provided with flattened projecting terminals 9, which are adapted to engage the stationary terminals 5. The caps 7 are provided with the usual ventilating openings 8, at least one of which is located in alinement with the flattened terminal 9. The handle for the fuse which embodies my invention comprises an insulated hand-grip 10, to the ends of which are secured similar brackets 11 by screws 12. The lower ends of the brackets are slotted at 13 and are adapted to slip over the terminals 9. The brackets 11 are also provided with inwardly extending lugs 14

which may conveniently be punched from the metallic bracket and each of which is adapted to engage one of the openings 8 in alinement with the terminal 9, to which openings the lugs are guided by the slotted ends of the brackets passing over the terminals. The brackets 11 are made sufficiently flexible so that when the handle is placed in position the lugs 14 readily ride over the edge of the caps 7 and snap into the openings 8. This arrangement gives a positive action and it is quite difficult to disengage the lugs after they once snap into the openings. In order to disengage the handle, it is only necessary to pry one of the brackets 11 outward slightly when its lug will be disengaged from the corresponding opening.

It will be seen that the device embodying my invention is extremely cheap, as it comprises only an insulated bar, which may conveniently be made of hard wood, preferably treated in the manner above indicated, and two brackets which may be made of steel punchings, and that the same affords a ready means for removing the fuse from the fuse box.

In accordance with the provisions of the patent statutes, I have described the principles of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. A fuse remover comprising a handle of insulating material, and two brackets of flat spring metal secured thereto and extending transversely therefrom, the ends of said brackets being slotted and having lugs inturned toward one another and adapted to detachably engage the ends of a fuse.

2. A fuse remover comprising an insulating handle and brackets with lugs at their adjacent sides extending transversely from said handle, said brackets being resiliently flexible toward and away from one another, so that when the remover is applied to a fuse they will separate and allow the lugs to ride over the ends of the fuse and then return.

3. A fuse remover comprising an insulating handle and brackets extending transversely therefrom and having on their ad-

jacent sides elements resiliently movable away from and toward one another, so that when the remoyer is applied to a fuse they will separate and ride over the ends of a 5 fuse and then return.

4. In combination, a fuse base, contact terminals mounted thereon, an inclosed fuse provided with projecting terminals which are adapted to engage said contact terminals, and a handle for removing said fuse comprising an insulated hand-grip and spring brackets projecting therefrom which are adapted to engage said projecting terminals and to releasably secure the handle 15 to the fuse.

5. In combination, a fuse base, stationary contact terminals mounted thereon, an inclosed fuse comprising a shell, perforated caps covering the ends of said shell and terminals projecting from said caps which are adapted to engage said stationary contact terminals, and a handle for removing said fuse comprising an insulated hand-grip, brackets secured thereto which are adapted 20 to straddle said projecting terminals, and means associated with said brackets and cooperating with said ventilated openings for removably securing the handle to said fuse.

6. In combination, a fuse base, stationary

contacts mounted thereon, an inclosed fuse 30 comprising an elongated shell for the fuse having caps provided with ventilating openings for closing the ends of said envelop, and blade terminals on said caps adapted to engage said stationary contacts, and a handle 35 for removing said fuse comprising an insulated hand-grip, spring brackets secured thereto and adapted to be received over said projecting blade terminals, and lugs secured to said brackets and adapted to detachably secure said handle to said fuse.

7. An inclosed fuse having caps provided with ventilating openings and contact terminals projecting from the ends of said fuse, a handle comprising an insulated hand-grip, 45 brackets projecting therefrom which are adapted to straddle said terminals, a lug projecting from each of said brackets and adapted to engage one of the ventilating openings in said caps whereby the handle 50 is adapted to be detachably secured to said fuse.

In witness whereof, I have hereunto set my hand this 24th day of December, 1912.

OSCAR E. FORREST.
